UNITED STATES PATENT OFFICE.

WILLIAM K. HENRY, OF NEW BRITAIN, CONNECTICUT, ASSIGNOR TO P. & F. CORBIN, OF NEW BRITAIN, CONNECTICUT, A CORPORATION OF CONNECTICUT.

DOOR-HINGE.

No. 873,432.

Specification of Letters Patent.

Patented Dec. 10, 1907.

Application filed January 25, 1907. Serial No. 353,934.

To all whom it may concern:

Be it known that I, WILLIAM K. HENRY, a citizen of the United States, residing at New Britain, county of Hartford, Connecticut, 5 have invented certain new and useful Improvements in Door-Hinges, of which the following is a full, clear, and exact description.

My invention relates to improvements in door hinges, particularly useful in connection 10 with heavy doors to act as a support for the same in place of the usual hinge.

The object of the invention is not merely to provide a bearing of this type with anti-friction balls arranged to perform their usual 15 function, but rather it is to combine the several elements, including the anti-friction balls, in such a manner as to make a complete structure which is compact and designed to withstand severe strains in use.

20 In the accompanying drawing Figure 1 is a side elevation of the complete hinge. Fig. 2 is a vertical sectional elevation of the complete hinge. Fig. 3 is a plan view of the hinge, with the cover plate removed. Fig. 4 25 is a plan view of the cover plate. Fig. 5 is a side elevation of the spindle, detached.

A is the case, generally of cylindrical form and preferably made from cast metal. B is an annular flange at its upper edge.

30 D—D are vertical offsets or lugs on opposite sides of the body of case A. These lugs perform a double function; first, they perform the spline function in that when the device is inserted into a suitable cavity these 35 lugs or offsets will hold the case A against rotation, and second, they afford room for screw-holes arranged to receive machine screws employed to hold the cover plate in place in the manner hereinafter described.

40 E—E are screw-holes in the flange B, which permit of the use of ordinary wood screws (not shown) for securing the case in place. The center of the case is bored nearly through and at the bottom of said 45 bore there is provided a suitable annular ball-race F having balls G—G therein.

H is a spindle which rotatably fits the bore of case A in such a manner as to receive lateral support therefrom, while the lower end 50 of the spindle is supported upon the balls. That part of the spindle standing above the

flange B is reduced in diameter, so as to form a shouldered portion H'.

I is a cap plate or cover having a central bore of a size to fit the reduced portion of the 55 spindle, with the result that when the parts are assembled a portion of the side thrust may be taken by the cap plate I as well as by the sides of the bore in the case A. The cap plate I overstands the shouldered portion H' 60 and hence prevents the accidental removal of the spindle.

K—K are machine screws which may be employed to hold the cap plate in place, these screws passing through said cap plate and 65 into tapped openings coincident with the lugs D—D in the case.

If desired, the ball-race at the bottom of the bore may be formed, as shown, by a separable steel plate fitted in said bore. So also 70 a hardened steel washer may be placed between the lower end of the spindle H and the balls, to prevent undue wear. Such a bearing is especially adapted for use in connection with heavy doors, such as found in fire- 75 proof buildings, vaults and the like.

What I claim is:

1. In a door hinge, the combination with a case having a central bore therein extending partially through the same, and a series of 80 balls at the bottom thereof, of a spindle having a shouldered portion snugly fitting the bore and rotatably supported upon the balls therein, and a cover plate overstanding the end of the case and the shouldered portion 85 of said spindle.

2. In a door hinge, the combination with a substantially cylindrical case having off-set lugs integral with the outer surface thereof, and an annular flange at the upper end 90 thereof, said case having a central bore extending part way through the same, of a spindle having a shouldered portion rotatably fitted to said bore, anti-friction device between the lower end of the spindle and the 95 bottom of said case, and a removable cover plate overstanding the case flange nad shouldered portion of said spindle.

WILLIAM K. HENRY.
